DESIGN FOR A FLY CUTTER

Lawson A. Smith, Los Angeles, Calif., assignor to
Robert H. Clark, Los Angeles, Calif.

Application May 31, 1944, Serial No. 113,821

Term of patent 14 years

(Cl. D54—14)

To all whom it may concern:

Be it known that I, Lawson A. Smith, a citizen of the United States, residing in the city of Los Angeles, county of Los Angeles, and State of California, have invented a new, original, and ornamental Design for a Fly Cutter, of which the following is a specification, reference being had to the accompanying drawing, forming a part thereof.

Fig. 1 is a perspective view of the fly cutter showing my new design, showing one side of the cutter, and the other side being the same in appearance; and Fig. 2 is a bottom end view of the fly cutter.

I claim:

The ornamental design for a fly cutter, as shown and described.

LAWSON A. SMITH.
